BLOCK FORMING MOLD

Charles H. Rothmann, Closter, N. J., assignor
to American Curb-Gutter Block Co. Inc., New
York, N. Y., a corporation

Application January 19, 1929. Serial No. 333,606

2 Claims. (Cl. 25—121)

This invention relates to a block forming mold, and has for one of its objects to provide a novel and highly efficient machine of this character which shall be especially adapted to be used for the purpose of manufacturing the curb and gutter forming block constituting the subject matter of my copending application, filed July 12, 1928, and serially numbered 292,169.

The invention has for a further object to provide a mold of the character stated which shall be adapted to permit the concrete, from which the block is made, to be subjected to very high pressure so as to permit the block to be formed without pores and thus render it water proof and exceedingly strong.

The invention has for a further object to provide a mold of the character stated which will be adapted to permit the formed block to be easily and quickly removed therefrom.

The invention has for a still further object to provide a mold of the character stated which shall be adjustable to permit the formation of blocks of different widths and thicknesses.

With the foregoing and other objects in view, the nature of which will appear as the description proceeds, the invention consists in the construction, combination and arrangement of parts hereinafter fully described and claimed, and illustrated in the accompanying drawings, where-

in:

Figure 1 is a view in front elevation of the mold;

Figure 2 is a top plan view of the mold;

Figure 3 is a sectional view taken on the vertical plane indicated by the line 3—3 of Figure 2;

Figure 4 is a sectional view taken on the vertical planes indicated by the line 4—4 of Figure 3;

Figure 5 is a sectional view taken on the horizontal plane indicated by the line 5—5 of Figure 1;

Figure 6 is a sectional view taken on the vertical planes indicated by the lines 6—6 of Figure 3;

Figure 7 is a view similar to Figure 3 with the door or front side of the mold in opened or lowered position;

Figure 8 is a sectional view taken on the horizontal plane indicated by the line 8—8 of Figure 3;

Figure 9 is a detail perspective view of the door of the mold, pallet and face plate.

Figure 10 is a detail perspective view of the core plate of the mold, and

Figure 11 is a detail view partly in section, illustrating a fragment of the face plate supporting means.

The mold which is indicated in general by the numeral 1 is made from metal and mounted

upon a concrete base 2. The mold 1 comprises a rear wall 3, side walls 4 and a front wall or door 5. The side walls 4 are provided at their front and rear edges with outwardly directed reinforcing and strengthening flanges 6. The flanges 6 extend throughout the entire height of the side walls 4. Bolts 7, functioning to retain the rear wall 3 and the side walls 4 in assembled relation, pass through the rear wall and through those flanges 6 that are located at the rear edges of the side walls. The lower end portions of the rear wall and the side walls 4 are embedded in the concrete base 2. Anchoring elements 8 of angular formation in cross section and embedded in the concrete base 2, are located outwardly beyond the side walls 4 between the flanges 6, and are secured to said walls by rivets 9.

Horizontally disposed angle bar brackets 10 are arranged inwardly of the side walls 4, and are secured to said side walls by rivets 11. The brackets 10 extend from the front edges of the side walls 4 to the rear wall 3, and are provided in their horizontal members with longitudinally extending series of openings 12. Hinge lugs 13 rest upon the brackets 10 and are each secured in place by a pair of bolts 14. As each of the brackets 10 is provided with a longitudinally extending series of openings 12, through a pair of which the bolts 14 of each hinge lug 13 pass, the hinge lug is capable of adjustment horizontally toward and away from the rear wall 3.

The door 5 is carried by straps 15 which are provided at their lower ends with hinge lugs 16 connected to the hinge lugs 13 by pintle 17. The door 5 is secured in closed or raised position by bolts 18 which are slidably carried by the hinge straps 15 for movement into and out of engagement in an aligned pair of the series of openings 19 formed in the side walls 4. The bolts 18 are yieldingly held in projected position by springs 20 and are adapted to be retracted from engagement with the side walls 4 through the medium of handles 21. The bolts 18 are horizontally aligned and the handles 21 thereof are arranged at their inner or adjacent ends so as to permit both of the bolts to be simultaneously retracted by one hand. Due to the adjustable mounting of the hinge knuckles 13 and to the provision of the side walls 4 with the series of openings 19, the door 5 may be secured in closed or raised position at different distances from the rear wall 3, whereby to adapt the machine for making blocks of different thicknesses. An angle bar 22, adapted to support the door 5 in horizontally opened or lowered position, extends across the front edges of the side walls 4 with its horizontal member arranged in a plane below the pintles 7, and is secured to the front flanges 6 by bolts 23.

The mold is provided with a core plate 24 which is removably secured to the rear wall 3 and to one of the side walls 4 by bolts 25. The core plate 24 has horizontally offset portions 24^a and 24^b. The portion 24^a is longer than the portion 24^b, and the latter portion is located rearwardly of the former. The intermediate or connecting portion 24^c of the core plate 24, is rounded at its points of juncture with the portions 24^a and 24^b.

A face plate 26 is carried by the door 5 and extends therefrom to the lower edge of the core plate 24. The face plate 26 is secured to the door 5 by an angle bar bracket 27 to which it is secured by bolts 28 and which is secured to the door by bolts 29. The door 5 is provided with vertical series of bolt receiving openings 30 in order to permit the face plate 26 to be adjusted vertically on the door and thus adapt the mold for making blocks of different widths. The rear edge of the face plate 26 conforms in contour to the horizontal contour of the core plate 24 in order to permit the door 5 to be opened and closed. To prevent any downward bending or flexing of the face plate 26, under the strain to which it will be subjected when the block material is being tamped, supports 31 are provided for the rear edge of the face plate, one of the supports being arranged adjacent one side edge 30 of the face plate and the other adjacent the other side edge thereof. The supports are in the form of bolts, and are threadedly engaged with bars 32 arranged below the face plate 26 and secured to the side walls 4. The supports 31 are provided with enlarged upper ends 31^a upon which the face plate 26 rests, and due to their screw threaded engagement with the rods 32 they may be adjusted vertically to support the rear edge of the face plate 26 in any adjusted position of the plate.

A pallet 33 rests upon the face plate 26 against the inner face of the door 5. The core plate 24 is provided with a wear plate 34, and wear plates 35 extend from the wear plate 34 to the pallet 33. These wear plates are removably secured in place by bolts 36 to permit the wear plate 34 and wear plates 35 to be renewed when scratched or otherwise unfit for further use, and to permit wear plates of different sizes to be substituted for the others when adjusting the mold for blocks of different sizes.

With the door 5 closed and secured in position by the bolts 18, and after the concrete has been poured into the space between the door and core plate 24, the concrete is tamped by any suitable apparatus of the electric motor operated type. After the tamping operation, the bolts 18 are retracted and the door 5 is lowered onto its rest or support 22, as clearly shown in Figure 7. The block which is of the form shown in Figure 9, may now be removed easily. As the door 5 is mounted for adjustment and latching at different distances from the core plate 24, blocks of different thicknesses may be made. As the face plate 26 is secured to the door 5 for vertical adjustment thereon, blocks of different widths may be made. In other words, by adjusting the door 5 with respect to the core plate 24 and by adjusting the face plate 26 upwardly or downwardly on the door 5, a block of the required thickness and width may be made. The machine will be equipped with wear plates of different sizes, the size of the wear plates

used in the machine depending solely on the size of the block to be made.

The block comprises a thick horizontal member or gutter portion 37 and a thick vertical member or curb portion 38. The gutter portion 37 is of narrow polygonal formation in plan, and the curb portion 38 extends transversely of and upwardly from the rear end of the gutter portion. The curb portion 38 is equal in height to the thickness of the gutter portion 37, and its thickness is greater than its height. The curb portion 38 gradually decreases in thickness outwardly from a point slightly above the gutter portion 37 so as to reinforce the portions at their point of juncture. This thickened part 39 is concave to effect better drainage and clearing of the gutter. As the block is of elongated polygonal formation in plan, it may be easily and quickly laid and laid at comparatively small cost. Due to the relative proportions of the parts thereof, the blocks are exceptionally strong, durable and efficient.

While I have described the principle of the invention, together with the structure which I now consider to be the best embodiment thereof, I wish it understood that the structure shown is merely illustrative and that such changes may be made when desired as are within the scope of the invention as claimed.

What I claim is:

1. A mold of the character set forth, comprising a mold having a rear wall and side walls, horizontal brackets secured to the inner surfaces of the side walls, hinge lugs arranged on the brackets for adjustment toward and away from the rear wall, means for securing the hinge lugs in an adjusted position, hinge straps pivotally connected to the hinge lugs, a door secured to the hinge straps, latch bolts carried by the door and engageable with the side walls to secure the door in closed position, a core plate secured within the mold, a face plate, means securing the face plate to the door for adjustment thereon, and adjustable supporting elements for the rear edge of the face plate.

2. A mold for plastic blocks comprising a rear wall, side walls extending from said rear wall, a frame having a cross bar secured at its ends against front edge portions of said side walls and side bars extending into the mold and secured against inner faces of the side walls, said frame

serving to brace the mold and its cross bar having an outwardly projecting flange, a front wall constituting a door fitting between the side walls, hinges for said door having straps secured vertically against the outer face of the door and lugs pivoted to the straps and resting upon said side bars, said lugs being releasably secured to the side bars for adjustment toward and away from the rear wall and said straps being adapted to rest upon the flange of the cross bar and support the door when the door is swung downwardly to an open position, a face plate projecting from said door and having depending attaching means at one end detachably secured against the door for adjustment of the face plate vertically in the mold, means for releasably securing the door in an upright closed position, and means in the mold to engage beneath the face plate and support the frame at its inner free end when the door is in an upright position.

CHARLES H. ROTHMANN.
